UNITED STATES PATENT OFFICE

95,878

DESIGN FOR A TENNIS RACKET OR SIMILAR ARTICLE

Martial Van Schelle, Brussels, Belgium, and
James Allen, London, England

Application December 6, 1934, Serial No. 54,324
In Belgium October 26, 1934

Term of patent 14 years

To all whom it may concern:

Be it known that we, Martial Van Schelle, a subject of the King of Belgium, residing at Brussels, Kingdom of Belgium, and James Allen, a subject of the King of England, residing at London, Kingdom of Great Britain, have invented a new, original, and ornamental Design for a Tennis Racket or Similar Article, of which the following is a specification, reference being had to the accompanying drawing, forming part thereof, and in which:

The ornamental design for a tennis racket or similar article as shown.

MARTIAL VAN SCHELLE.
JAMES ALLEN.
